UNITED STATES PATENT OFFICE

118,989

DESIGN FOR A PACKAGE ENVELOPE OR SIMILAR ARTICLE

Leroy L. Salfisberg, South Orange, N. J. assignor
to Ivers-Lee Company, Newark, N. J., a cor-
poration of Delaware

Application April 27, 1939, Serial No. 84,591

Term of patent 14 years

To all whom it may concern:

Be it known that I, Leroy L. Salfisberg, a citizen of the United States and a resident of South Orange, in the county of Essex and State of New Jersey, have invented a new, original, and ornamental Design for a Package Envelope or Similar Article, of which the following is a specification, reference being had to the accompanying drawing, forming part thereof.

Figure 1 is a plan view of a package envelope showing my new design.

Figure 2 is an edge elevational view of the package envelope, and

Figure 3 is an enlarged fragmentary transverse sectional view on the line 3—3 of Figure 1.

The dominant features of the design reside in the square wafer-like shape, the series of alternate ribs and grooves concentric with a central frusto-conical protuberance at each of opposite sides of the package envelope bordered by the diagonal alternate ribs and grooves intersecting the edges of the package envelope and terminating short of the outermost one of said concentric ribs and grooves.

I claim:

The ornamental design for a package envelope or similar article, as shown and described.

LEROY L. SALFISBERG.
